WINDOW CONSTRUCTION

George A. Kreuscher, Kenosha, Wis., assignor to
 W. J. Dennis & Company, Chicago, Ill., a corporation of Illinois

Application January 13, 1937, Serial No. 120,417

8 Claims. (Cl. 20—12)

This invention relates to window construction, and particularly to novel means for positioning the sash members thereof in the window casing, and for facilitating the movements of the sash with respect thereto.

One object of the present invention is to provide novel means for obtaining a substantially weather-tight connection between the window casing and the sash slidably mounted therein.

Another object of the invention is to provide a resilient member engaging the casing and sash with a yielding pressure to produce a cushioning effect in all directions laterally of the sash and in a manner to prevent rattling, binding or sticking of the sash within the casing, and to compensate for expansion and contraction of the sash rails and casing.

Another object of the invention is to provide a resilient member adapted to be positioned, under tension, between the side portions of the casing and the side edge portions of the sash in a manner to engage both the casing and sash yieldingly, and with a pressure intended to provide a weather-tight connection between the respective elements and to assist in maintaining the window sash in various positions of adjustment with respect to the casing.

Another object of the invention is to provide a resilient member between the side portions of the casing and sash, and having an elongated projection adjacent its central longitudinal portion forming an intermediate stop member between adjacent faces of the respective sash.

Another object of the invention is to provide novel resilient means operatively related to the window casing and sash for counter-balancing and assisting in positioning the sash in various positions of adjustment with respect to the casing.

Another object of the invention is to provide a counter-balancing device embodying resilient members wherein a substantially uniform tensioning of the said members is obtained throughout substantially the entire raising and lowering movement of the sash.

A further object of the invention is to provide a novel combination of operatively related compression and tension springs connected, respectively, to the sash and casing of the window structure in a manner to facilitate the removal of the springs for purposes of repair or replacement.

A still further object of the invention is to improve a structure of the character described

in sundry details hereinafter referred to and particularly pointed out in the appended claims.

One embodiment of the present invention is shown for illustrative purposes in the accompanying drawings, in which:

Fig. 1 is an inside perspective view of a window casing and sash members therefor embodying features of the present invention;

Fig. 2 is an enlarged transverse plan sectional view through a portion of Fig. 1, and taken substantially as indicated by the line 2—2 thereof;

Fig. 3 is an enlarged fragmentary sectional view taken substantially as indicated by the line 3—3 of Fig. 1, and showing portions of the upper and lower sash members adjacent each other or in window closing position;

Fig. 4 is a perspective view of an elongated resilient metal strip or member forming a part of the present invention;

Fig. 5 is an enlarged transverse plan sectional view taken substantially as indicated by the line 5—5 of Fig. 4;

Fig. 6 is an enlarged vertical sectional elevational view taken substantially as indicated by the line 6—6 of Fig. 1;

Fig. 7 is an enlarged plan sectional view taken substantially as indicated by the line 7—7 of Fig. 1;

Fig. 8 is a further enlarged sectional elevational view taken substantially as indicated by the line 8—8 of Fig. 7, and illustrating the relationship of my improved counter-balancing means to the casing and sash members of the window construction;

Fig. 9 is a separated or exploded view of related elements embodied in the counter-balancing means of the structure illustrated in Fig. 8; and

Fig. 10 is a vertical sectional elevational view of a slightly modified counter-balancing structure, of which the present invention is susceptible.

In the illustrative embodiment, the present invention is shown in its relation to a window construction comprising a casing indicated, as a whole, by the numeral 11, and having laterally spaced vertically disposed substantially parallel inner and outer stop members 12 and 13, respectively, secured thereto at opposite sides of the casing, and provided also with inner and outer or lower and upper sash members indicated, as a whole, and respectively, by the numerals 14 and 15 slidably mounted in the casing 11 adjacent the respective inner and outer stops 12 and 13 thereof.

For providing a weather-tight connection between the casing and sash members 14 and 15, 55

an elongated strip or member indicated, as a whole, by the numeral 16, and formed, preferably, of resilient material such, for example, as resilient sheet metal or the like, is positioned 5 between the casing 11 and sash members 14 and 15 in a manner to position the end portions 17 of the member 16 in engagement with the casing 11 between the stops 12 and 13. The member 16 is provided intermediate the longitudinal edge 10 portions thereof, preferably, adjacent its central longitudinal portion, with a projection 18 forming a hollow intermediate stop adapted to be positioned between adjacent faces of the sash members 14 and 15 in a manner to provide a 15 guide for maintaining the opposite faces of the sash members in operative engaging position with respect to the stops 12 and 13, respectively.

It will be noted by reference to Fig. 5 that the member 16, generally speaking, is normally of 20 substantially bow-like form in cross-section and, by reference to Figs. 2 and 7, that when placed in position between the casing 11 and sash members 14 and 15, the member 16 is slightly flattened for placing the material thereof under 25 spring tension in a manner to exert a pressure against the edge portions of the sash members 14 and 15 for providing a weather-tight connection between the casing and sash, the member 16 being also free to yield with lateral movement 30 of the sash members in a manner to prevent rattling or binding of the sash members within the casing, it being understood that owing to the resiliency of the member 16 and tension exerted thereby, the sash members 14 and 15 will be urged 35 against the stops 12 and 13 as illustrated in Figs. 2 and 7.

Fig. 3 illustrates a structure for providing a 40 weather-tight connection between the upper rail of the sash member 14 and the lower rail of the sash member 15, wherein a weather strip 28 is secured to the sash member 15, and adapted to extend laterally therefrom and to underlie the upper rail of the sash member 14 as indicated at 38.

It will be observed from the foregoing description 45 that the present invention comprises a novel construction and arrangement for producing a weather-tight connection between the casing and sash members, also that by reason of the resilient character of the member 16, binding or sticking 50 of the sash is overcome, the sash members are secured against rattling, and the pressure exerted by the resilient member 16 assists in retaining the sash members in various positions of adjustment 55 with respect to the casing 11.

It will be observed also that by reason of the 60 resiliency of the member 16, the yieldability of the member will compensate for the expansion and contraction of the sash rails, and at the same time maintain a weather-tight connection 65 between the window casing and sash.

For providing a counter-balance to assist in 70 positioning the sash members 14 and 15 in various positions of adjustment with respect to the casing 11, each of the sash members is provided at its corners adjacent the opposite sides of the sash with a recess 19 having an L-shaped 75 spring metal angle member 21 positioned therein in a manner to form a resilient wear-piece for engaging the stops 12 and 13 and to provide a channel for receiving a tubular member 22 slidably mounted in a recess 23 formed in a plate 24 adapted to be secured by means of screws 24a to the upper edge portion of the sash members 14 and 15, the tubular member 22 being vertically

movable in the recess 23 and provided adjacent its upper end with an annular flange 25 for limiting the downward movement of the tubular member 22 with respect to the plate 24 and respective sash members 14 and 15.

As illustrated in Figs. 6 and 8, the tubular member 22 is provided adjacent its lower end portion with a connecting member 26 having a laterally extending flange or shoulder 27 formed thereon and extending beyond the surface of the 10 tubular member in a manner to be engaged by the lower end of a compression spring 28 surrounding the tubular member 22, the upper end of the spring 28 being adapted to engage the lower surface of the plate 24 and to be secured 15 against accidental displacement with respect thereto by means of an upwardly extending portion 29 (Fig. 9) formed on the end of the spring and adapted to engage an aperture 31 formed in the plate.

Positioned within the tubular member 22 is a tension spring 32 having its lower end portion operatively secured to the connecting member 26 and its upper end portion adapted to extend beyond the upper end of the tubular member 22 25 and connected to the upper rail 33 of the casing 11 by means shown, in the present instance, as a screw-eye 34.

By such an arrangement, it will be apparent 30 that upon the initial downward movement of the upper sash member 15, the tension spring 32 will be extended to a point where the tension thereof is substantially equal to that of the compression spring 28 surrounding the tubular member 22, at which time the spring 28 will start to 35 compress, and the tubular member 22 will be moved upwardly through the recess 23 in the plate 24 as illustrated in Fig. 8, and as the spring 28 is further compressed between the shoulder 27 and plate 24, the tension spring 32 will be 40 lengthened correspondingly to permit the lowering of the sash 15 as may be desired, and at the same time the lowering of the sash will act to store sufficient energy in the tension spring 32 and the compression spring 28 to assist in raising 45 the sash 15 when it is desired to return the sash to its normal upper or closed position.

From the foregoing description it will be observed 50 that the present invention provides a novel construction and arrangement of resilient or spring devices functioning to facilitate the raising of the lower sash, and in combination with the resilient member 16 and the force exerted thereby provides a novel arrangement whereby the sash may be readily retained in desired position with respect to the casing 11.

Referring particularly to Fig. 10, the structure 60 illustrated therein comprises a casing 11a having a top rail 33a and a sash member 15a slidably mounted in the casing, the member 15a being 65 provided with a recess or groove 19a adapted to receive a tubular member 22a secured rigidly therein, preferably, by means of a screw 35 extending through one side of the tubular member 22a, the opposite side of the tubular member being 70 provided with an aperture 36 through which the screw 35 may be positioned in the sash member 15a for securing the tubular member 22a rigidly thereto.

Positioned within the tubular member 22a is a 75 compression spring 28a having its upper end portion in engagement with an inwardly extending shoulder 24b formed adjacent the upper portion of the member 22a, and its lower end portion engaging a shoulder or flange 27a formed on a 80

connecting member 26a longitudinally movable within the tubular member 22a. Positioned within the compression spring 28a is a tension spring 32a having its lower end portion secured by means of a screw-eye 31 to the connecting member 26a, and its upper end operatively connected to the upper rail 33a of the casing 11a by means of a screw-eye 34a, the arrangement of the compression spring 28a and tension spring 32a being such that as the sash member 15a is lowered, the tension spring 32a will be extended and the compression spring 28a compressed within the tubular member 22a for storing energy in the springs to assist in raising the sash substantially in the same manner as described with reference to the structure illustrated in Fig. 8, the structure illustrated in Fig. 10 being substantially like that illustrated in Fig. 8 except that both springs are positioned within the tubular member 22a and the tubular member of Fig. 10 is secured against relative movement with respect to the sash member 15a.

It will be observed from the foregoing description that the present invention further provides a novel combination of operatively related compression and tension springs operatively connected, respectively, to the sash and casing of a window structure for counter-balancing the weight of the sash, and in a manner to facilitate the removal of the springs for purposes of repair or replacement.

Obviously, the present invention is not limited to the precise construction and arrangement shown and described, as the same may be variously modified. Moreover, all the features of the invention need not be used conjointly as the same may be used to advantage in variously different combinations and sub-combinations.

What I claim as new and desire to secure by Letters Patent is:

1. In a window, the combination with a casing having laterally spaced substantially parallel inner and outer stops rigidly secured thereto, of an elongated member formed of resilient material positioned between said stops and laterally movable with respect to the sides of said casing and having oppositely disposed free edge portions movable toward and away from said stops, said member having an elongated substantially U-shaped projection adjacent its central longitudinal portion and forming a hollow intermediate stop, and upper and lower sash members slidably mounted, respectively, between said intermediate stop and the inner and outer stops secured to said casing.

2. In a window, the combination with a casing having inner and outer stops rigidly secured thereto, of an elongated member formed of resilient material positioned adjacent its edge portions against the side of said casing between and in spaced relation inwardly with respect to said stops, said member having an elongated substantially U-shaped projection adjacent its central longitudinal portion and forming a hollow intermediate stop, the portion of said member adjacent said projection being spaced from the side of said casing and laterally movable with respect thereto, and upper and lower sash member slidably mounted, respectively, between the opposite sides of said intermediate stop and the inner and outer stops secured to said casing.

3. In a window, the combination with a casing having inner and outer stops rigidly secured thereto, of an elongated member formed of resilient material and normally of bow-shaped cross-

section positioned between said stops with the longitudinal edge portions of the member in engagement with the side portions of said casing and in spaced relation to said inner and outer stops, said member having an elongated substantially U-shaped projection adjacent its central longitudinal portion and forming a hollow intermediate stop, and upper and lower sash members having a portion of their side edges spaced from an adjacent portion of said member and slidably mounted, respectively, between said intermediate stop and the inner and outer stops secured to said casing, the engagement of said sash with said elongated member tending to flatten the member in cross-section and place the material thereof under tension in a manner to yieldably engage the side edge portions of said sash.

4. In a window, the combination with a casing having inner and outer stops rigidly secured thereto and having upper and lower sash members slidably mounted in said casing, of an elongated resilient metal strip of normally bow-shaped cross-section having elongated free edge portions slidably engaging said casing, said strip being positioned under tension against said casing by said sash members intermediate said stops, and a projection on said strip adjacent the central longitudinal portion thereof forming an intermediate stop positioned between said sash members.

5. In a window, the combination with a casing having inner and outer stops rigidly secured thereto and having upper and lower sash members slidably mounted in said casing, of an elongated resilient metal strip of normally bow-shaped cross-section positioned under tension against said casing by said sash members intermediate said stops with both of its edges free to slide laterally on the casing, and an elongated substantially U-shaped projection formed on said strip adjacent the central longitudinal portion thereof and forming a hollow intermediate stop positioned between said sash members.

6. In a window, the combination with a casing having inner and outer stops rigidly secured thereto and having upper and lower sash members slidably mounted in said casing, of an elongated resilient metal strip of normally bow-shaped cross-section positioned under tension between said casing and the edge portions of said sash members intermediate said stops and in spaced relation thereto, and an elongated substantially U-shaped projection with relatively movable sides formed integrally with said strip adjacent the central longitudinal portion thereof and forming a hollow intermediate stop positioned between adjacent faces of said sash members and movable laterally thereby and with respect to said inner and outer stops.

7. In a window, the combination with a casing having inner and outer stops secured thereto and having upper and lower sash members slidably mounted in said casing, of an elongated member formed of resilient sheet-like material positioned under tension between said casing and sash members intermediate said stops and having an elongated projection adjacent its central longitudinal portion forming an intermediate stop between said sash members, said elongated member having longitudinal side edge portions engaging the side of said casing between said stops and both slidably movable on said casing toward and from said inner and outer stops.

8. In a window, the combination with a casing having inner and outer stops secured thereto and

- 5 having upper and lower sash members slidably mounted in said casing, of an elongated member formed of resilient sheet-like material positioned under tension between said casing and sash members intermediate said stops and having an elongated projection adjacent its central longitudinal portion forming a resilient intermediate stop between said sash members adapted to yieldingly

urge the respective sash members towards said stops, said elongated member having longitudinal side edge portions engaging the side of said casing between said stops and both slidably movable on said casing toward and from said inner and outer stops.

GEORGE A. KREUSCHER.
